HAND WEAPON

Carl R. Weinert, Pittsburgh, Pa., assignor to Federal Laboratories, Inc., Saltsburg, Pa., a corporation of Pennsylvania

Application April 30, 1956, Serial No. 581,692

2 Claims. (Cl. 42—1)

This invention relates to a single shot hand weapon for firing fixed ammunition, particularly gas cartridges.

Although primarily a tear gas gun, the weapon of the present application also embodies the dual function feature of a policeman's club of the type generally as shown in expired gun patent U. S. No. 1,598,784. Owing to the fact that such guns are smooth bore weapons within the 10 or 12 gauge range in terms of shotgun standards, it is important that if these guns fall into the wrong hands they do not become death dealing weapons with the mere insertion of a shotgun shell or of other standard ammunition of appropriate size into their cartridge chamber. Compared to the referred to gun in U. S. Patent No. 1,598,784 which employs an electrically fired cartridge and a battery firing system therefor, the present weapon uses the more conventional percussion firing system, yet embodies novel structure specifically retaining that desired safety feature of ineffectuality with standard percussion ammunition.

A preferred embodiment of the invention is shown in the accompanying drawing in which in general:

Figure 1 is a side view, with portions broken away, showing my weapon embodied in a policeman's club, and

Figure 2 is an enlarged fragmentary showing of a broken away portion of Figure 1.

More specifically in the embodiment of the drawing, I combine a gas gun and policeman's club into one weapon consisting of breech and barrel parts 10, 12 with a threaded joint 14 therebetween and an included chamber 16 to receive a cartridge 18 of fixed ammunition. The breech part 10 has a cocking plunger 20 which at its outer end carries a pull knob 22 to cock the weapon. A firing button 24 at the side of the breech part has a retractable cover 26 serving as its safety guard and sliding between safety and firing positions between a pair of guide plates 28 affixed to the breech part. The breech part 10 has a tubular metal case 30 containing a breech block 32 secured to the interior thereof and having a centrally disposed firing pin aperture 34. At one end of the aperture 34 the breech block 32 is counterbored to define a stop shoulder 36 for the stop collar 38 on a round pointed firing pin 40. The firing pin 40 has a firing pin plunger 42 surrounded by a firing spring 44 engaging an abutment 46 which is carried by the firing pin plunger 42. The outside of the breech block 32 has an undercut cylindrical portion 48 terminating in a transverse annular shoulder 50 which abuts a portion of the shell 18 and which has a central recess providing a socket 52 to receive another portion of the shell 18. The firing pin aperture 34 intersects the floor of the recess 52 at the center. The full path of travel of the firing pin 40 is from the solid line position shown in Figure 2 to a limiting point at which the stop parts 36, 38 engage one another and which is indicated by the dotted lines 40a between the floor of the recess 52 and the plane of the shoulder portion 50.

The cartridge 18 has a cylindrical case with an open

2

end 54 which may be partially spun over and a closed breech end 56. It may be made as a unitary assembly by press fitting a plug in one of the open ends of a metal tube, but preferably this shell case is a one-piece aluminum extrusion of uniform diameter generally throughout its length and pierced at the thick walled breech end which constitutes all that remains of the parent aluminum slug which underwent extrusion. The cartridge 18 has a self-contained charge 58 therein consisting of a rear section of propellant powder and a longer section of gas charge powder which liberates tear gas when fired. An intermediate wafer of wadding 59 separates the propellant powder section from the long front section of gas charge powder which further has an end wafer of wadding 60 at the front to retain it in the shell after being loaded through the open end 54 and compacted. Externally thereof, the closed breech end of the cartridge 18 carries a circular rear rim 62 and a center boss 64 which protrudes axially beyond the rear of the radially protruding rim and is socketed in the center recess 52 in the breech block 32. Internally, the closed breech end 56 carries a flanged primer 66 permanently socketed in a center bore in the boss 64 in alignment with the firing pin aperture 34 and extending rearwardly beyond the plane of the rim 62 so as to be directly across the path of travel of the firing pin 40.

The barrel part 12 includes a cylindrical tube 68 having an outer shoulder 70 which positively abuts the breech part 10 and an inner shoulder 72 which confronts the annular shoulder 50 on the breech block 32, the confronting shoulders being arranged to clamp the shell 18 with the rear rim 62 thereof in the plane therebetween. The cylindrical tube 68 carries a tapered sleeve 74 disposed on the outside thereof and covered by a series of leather rings 76.

In operation of the weapon, the operator retracts the pull knob 22 to cock the weapon and depresses the firing button 24 to fire it. After discharge, the breech and barrel parts are unscrewed at the joint 14 and the operator slips out the old cartridge and inserts a new one. Conceivably, standard ammunition from the shelf of a hardware store may be inserted in the weapon in place of the cartridge 18. Although each such cartridge is basically a round of center fire ammunition like the cartridge 18, the firing pin 40 will not fire the standard ammunition because its travel is interrupted due to the engagement between the stop shoulder 36 and the stop collar 38 which bottoms and thus limits forward travel of the firing pin 40. The shape of the recess 52 is not critical so long as the center boss 64 on the cartridge 18 can readily be socketed therein and they both may be round or else polygonal or otherwise noncircular in shape. The offset of the center boss and the primer 66 beyond the plane of the rim 62 is important, however in order that the latter primer 66 will extend to a point in the path of travel of the firing pin 40. So long as the socket and boss 64 are provided, other firing means such as a hammer of the revolver type may be used.

While I have described certain presently preferred embodiments of my invention, it is to be understood that it may be otherwise embodied within the scope of the following claims.

I claim:

1. In a policeman's club breech chamber construction, the combination of a shell in the chamber, said shell having a firing primer and a rim at the rear and a centrally disposed metal primer boss offset behind the rim holding the primer protectively therewithin, and breech and barrel parts detachably joined together to form the cartridge chamber and presenting closely spaced confronting surfaces one with a central recess to exclusively

receive the primer boss, each part having a shoulder portion offset from said central recess and cooperating with the other shoulder portion to clamp the shell with the rim thereof in a plane immediately therebetween, said breech part further having a firing pin bore with its mouth intersecting the floor of the recess, and a firing pin retractable in the bore from a fired position with the point occupying said recess to a cocked position behind the mouth of said bore.

2. In a breech chamber construction, the combination of a shell in the chamber, said shell having a firing primer and a rim at the rear and a centrally disposed metal primer boss offset behind the rim holding the primer protectively therewithin, and breech and barrel parts detachably connected together to form the cartridge chamber and presenting closely spaced confronting surfaces one with a central recess to exclusively receive the primer boss, each part having a shoulder portion offset

from said central recess and cooperating with the other shoulder portion to clamp the shell with the rim thereof in a plane immediately therebetween, said breech part carrying a firing pin and further having a registering firing pin bore with its mouth intersecting the floor of the recess, and stop means to permanently limit forward travel of the pin to a point between the floor of the recess and the corresponding rim clamping shoulder.
